(57) **CLAIM**

An ornamental design for a conduit end, as shown and described.

DESCRIPTION

FIG. 1 is a top elevation view of a conduit end showing my new design, the side elevation view being a mirror image; FIG. 2 is an enlarged fragmental view thereof, taken from FIG. 1;

FIG. 3 is a top view thereof, shown in an alternative configuration; the side elevation view being a mirror image; and,

FIG. 4 is an isometric view thereof.

The broken lines shown represent unclaimed subject matter and form no part of the claimed design.

A coated conduit end comprising a male threaded portion, a first portion abutting the male threaded portion and a second portion abutting the first portion, wherein the first and second portions are distinguished from each other by a perceivable demarcation.
